United States Patent Office.

RILEY JAMES GILBERT, OF HANOVER, WISCONSIN.

Letters Patent No. 69,336, dated October 1, 1867.

IMPROVEMENT IN GATES.

The Schedule referred to in these Letters Patent and making part of the same.

TO ALL WHOM IT MAY CONCERN:

Be it known that I, RILEY JAMES GILBERT, of Hanover, Rock county, and State of Wisconsin, have invented a new and improved Gate; and I do hereby declare that the following is a full and exact description thereof, reference being had to the accompanying drawings, and to the letters of reference marked thereon, making a part of this specification, in which—

Figure 1 is a perspective view.

Figure 2 is a cross-section of the inclined way G, showing how the upright piece A is supported thereby.

Figure 3 is a cross-section of the inclined way H, showing how the upright piece K is supported thereby.

Figure 4 is also a sectional drawing, showing how the gate is operated by the handles and cords; and

Figure 5 is a view from the side opposite to that shown in fig. 1 of simply the gate and the ways.

The nature of my invention consists, first, in separately supporting and guiding each end of the gate on parallel double inclined ways, constructed substantially as hereinafter described; and second, in operating a gate supported on two parallel double-inclined ways, by means of handles and cords provided with stops, in such a manner that the gate is operated, not only by the cord, but by its own momentum and gravity, substantially as hereinafter described.

To enable others skilled in the art to make and use my invention, I will proceed to describe its construction and operation.

I construct my gate in any desired form, providing it with the upright piece A, to which is secured a friction-pulley, d, fig. 2, that runs on the rail or track piece c of the double-inclined way G, which in turn is supported at each end by the posts C and C'. The other end of the gate plays between the vertical guiding rollers L and M, (attached to the post C'), and is supported in a similar manner as the outer end of the gate by a pulley, d', fig. 3, that is attached to the upright piece K, and runs on the rail or track piece c' of the double-inclined way H. Through a slot or mortise in the upper end of the upright piece A passes the central portion of the rope D, that is secured to the upright piece by a pin, or in any desired manner. The ends of this operating cord D passing out on either side through or between the friction-pulleys, shown at P, or more fully shown in figs. 2 and 4, are carried over the pulleys h, that are attached to the arms of the posts F. Both ends of the cord D are provided with a knot or stop, f, that will not pass over the pulley h. These stops are so arranged as to strike against the pulley or side of the arm of the post, when the upright piece A has arrived at the position shown by the dotted line A', fig. 1.

Were it not for the stops f the gate in the hands of the unskilled operator would not operate, inasmuch as continual pulling on either end of the cord would stop it at the apex or summit of the inclined ways; but, with the use of the stop, the force of the pull being taken off of the cord when the gate is at the dotted line A', the latter (that is the gate) is carried by its own momentum over the summit, and thence by gravity down the descending portions of the inclined ways.

What I claim is—

1. The inclined ways G and H, when constructed with ascending and descending inclines, and used to guide and support separately the ends of a gate, substantially as described.
2. Operating a gate, having its ends separately supported on two parallel double-inclined ways, by means of the handles E and cord D, the latter being provided with a stop, f, in such a manner that the gate is operated by the cord, together with its own momentum and gravity, substantially as described.

RILEY JAMES GILBERT.
